SPOTTING GUN

Filed Oct. 28, 1947

UNITED STATES PATENT OFFICE

2,606,069

SPOTTING GUN

Edwin L. Hutchins, San Diego, and Jack O. Butler, Chula Vista, Calif.; said Butler assignor to said Hutchins

Application October 28, 1947, Serial No. 782,614

3 Claims. (Cl. 299—86)

1

Our invention relates to a spotting gun, more particularly for use in connection with the cleaning of clothes or fabrics and the objects of our invention are:

First, to provide a spotting gun of this class which incorporates a multiple valve controlling a variety of cleaning fluids and solvents to be dispensed in combination with steam if desired for removing spots from clothing or fabric consisting of various chemical compositions.

Second, to provide a spotting gun of this class having very simple valve means employing a plurality of plungers each of which may be operated selectively for dispensing a certain fluid for a certain cleaning purpose.

Third, to provide a spotting gun of this class having a multiple plunger valve on the handle of the spotting gun controlled by one of the fingers of the hand holding the spotting gun whereby efficiency and speed of the operation is maintained together with the precise direction of the fluid from the valve through a dispensing tube to the fabric being cleaned.

Fourth, to provide a spotting gun of this class having immediate facilities for dispensing such cleaning fluids as carbon tetrachloride, neutral lubricant, paint remover, ink remover, ammonia, acetic solution and other well known cleaning fluids.

Fifth, to provide a spotting gun of this class which incorporates a steam nozzle adjacent to which is a valve outlet tube arranged to dispense a variety of fluids aspirated therefrom by the steam passing from the steam nozzle.

Sixth, to provide a spotting gun of this class having a multiple plunger valve and tubes connected therewith communicating with a plurality of individual containers holding a variety of cleaning fluids.

Seventh, to provide a spotting gun of this class in which a plurality of fluids may be conducted to the spotting gun through as many separate tubes communicating with a multiple plunger valve which is conveniently located on the handle of the spotting gun whereby extreme efficiency of spotting is accomplished and the fluids are properly directed in an economical manner.

Eighth, to provide a spotting gun of this class which is very simple and economical of construction, efficient in operation and which will not readily deteriorate or get out of order.

With these and other objects in view as will appear hereinafter, our invention consists of certain novel features of construction, combination and arrangement of parts and portions as will

2

be hereinafter described in detail and particularly set forth in the appended claims, reference being had to the accompanying drawing and to the characters of reference thereon forming a part of this application in which:

Figure 1 is a fragmentary side elevational view of our spotting gun; Fig. 2 is a fragmentary top or plan view thereof; Fig. 3 is a sectional view taken from the line 3—3 of Fig. 1 and Fig. 4 is a diagrammatic view of our spotting gun showing the tubular conductors communicating therewith and the receptacles from which said conductors are fed.

Similar characters of reference refer to similar parts and portions throughout the several views of the drawing.

The handle 1, steam nozzle 2, valve casing 3, valve plungers 4, 5, 6 and 21, tubes 7, 8, 9 and 10, plates 11, 12, 13 and 14, plugs 15, 16, 17 and 18, insulator 19 and valve outlet tube 20 constitute the principal parts and portions of our spotting gun.

The handle 1 is a cylindrical handle having insulating plates 1a and 1b at the rear and front ends thereof respectively through which the steam nozzle 2 extends concentrically thereof. Surrounding this steam nozzle 2 inwardly of the handle 1 is an insulator 19 arranged to prevent the exchange of heat from the steam nozzle 2 to the handle 1 normally grasped by the hand of the operator of our spotting gun. Secured to the side of the handle 1 is the valve casing 3 which is disposed rearwardly of the forwardly and laterally curved portion 2b of the steam nozzle 2. This steam nozzle 2 is provided with a substantially flattened open end portion 2c through which steam is projected. Adjacent to this curved portion 2b on the steam nozzle 2 is a curved portion 20a of the valve outlet tube 20 which is provided with an open end 20b adjacent to the open end 2c of the steam nozzle 2. The rearward end of this valve outlet tube 20 communicates with the interior of the valve casing 3 at its longitudinal bore portion 3a connecting the bore portions 3b of the valve plungers 4, 5, 6 and 21 in series. These valve plungers 4, 5, 6 and 21 control the flow of fluid from the tubes 7, 8, 9 and 10 respectively. Secured to the upper side of the valve casing 3 and surrounding the valve plungers 4, 5, 6 and 21 are the plates 11, 12, 13 and 14 respectively. Inasmuch as the valves 4, 5, 6 and 21 are substantially identical, the valve plunger 4 will be herein described in detail. Inwardly of the plate 11 and surrounding the stem 4a of the valve plunger

4 is a retainer gasket 4b. The bore portion 3b of the valve casing 3 surrounding the valve plunger 4 is slightly larger in diameter than the shank 4a of the valve plunger 4 permitting the flow of fluid therearound, communicating with the bore 3a. The head 4c, of the valve plunger 4 engages the gasket 4d in the enlarged bore portion 4e and prevents flow of fluid from the tube 7 when admitted intermediate the plug 15 and the head 4c of the valve plunger 4 when in the closed position as shown in Fig. 3 of the drawing. The spring 4f intermediate the plug 15 and the head 4c of the valve plunger 4 tends to hold the valve 4 in closed position. It will be noted that the plugs 15, 16, 17 and 18 enclose the enlarged bore portions of the valve casing 3 at the lower ends of the valve plungers 4, 5, 6 and 21 respectively. Communicating with the valves 4, 5, 6 and 21 and the tubes 7, 8, 9 and 10 communicating therewith are the receptacles 22, 23, 24 and 25 in which various solvents and cleaning fluids may be positioned such as carbon tetrachloride, neutral lubricant, paint remover, ink remover, ammonia, acetic solution and other similar cleaning fluids.

It will be noted that the tubes 7, 8, 9 and 10 extend to a position near the bottom of the containers 22, 23, 24 and 25 whereby siphoning of the fluid therefrom is accomplished when the respective valves in connection with the tubes 7, 8, 9 and 10 are opened causing the steam tube 2c to aspirate the fluid through the tube 20 at its open end 20b.

The operation of our spotting gun is substantially as follows:

When the operator of the spotting gun detects a certain spot on clothing requiring a certain solvent or cleaner, he presses one of the valve plungers 4, 5, 6 or 21 according to the particular fluid he wishes to dispense from the valve outlet tube 20a at its open end 20b adjacent the open end 2c of the steam nozzle 2. When the operator presses the particular valve plunger, fluid is drawn from one of the tubes 7, 8, 9 or 10 communicating with the bottom of one of the containers 22, 23, 24 or 25 each holding a separate and distinct cleaning fluid. The fluid is siphoned from one of the containers through the valve casing and dispensed in a precise manner at the open end 20b of the valve outlet tube 20. It will be noted that the bore 3a in the valve casing 3 communicates in series with the bore 3b in which the valve plungers 4, 5, 6 and 21 are reciprocally mounted permitting fluid to be dispensed from any one of the valve plungers through said common series tube 3a to the valve outlet tube 20. The gaskets 4b and 4d prevent escape of fluid around the valve plunger 4a when in closed or open position and the aspirating effect of the steam passing outwardly of the steam nozzle 2 at its open end 2c aspirates the fluid from the valve outlet tube 20 at its open end 20b. Thus, it is unnecessary to provide pressure containers for the fluid in the containers 22, 23, 24 and 25 but such pressurized fluid supply may be maintained if desired. The disposition of the valve casing 3 on the handle 1 of the spotting gun provides for the convenient handling of clothing with one hand and while performing the complete operation of steam spotting in combination with fluid spotting which may be precisely accomplished by the open end portions 2c and 20b of the steam nozzle 2 and valve outlet tube 20 respectively. Thus, efficiency of operation of spotting of clothing is greatly improved over

the method of dispending from bottles which is hazardous and which is very wasteful. It will be noted that in some cases the steam may be used following the application of the fluid to flush out the materials causing the stain in a fabric after said materials have been loosened by the solvent already applied through the valve outlet tube 20 at its open end 20b. It will be noted that the springs 4f in connection with the valve plungers as best shown in Fig. 3 of the drawing, provide for the quick return and positive closing of each of the valves after being depressed by the thumb pieces on the upper ends of said valves as shown best in Figs. 1 and 2 of the drawing. Thus, the dispensation of solvents or cleaning fluids through the valve casing 3 is accomplished only during the time that the valves are consciously depressed by the operator.

Though we have shown and described a particular construction, combination and arrangement of parts and portions we do not wish to be limited to this particular construction, combination and arrangement but desire to include in the scope of our invention, the construction, combination and arrangement substantially as set forth in the appended claims.

Having thus described our invention, what we claim as new and desire to secure by Letters Patent is:

1. In a spotting gun of the class described, the combination of a handle, a steam nozzle extending therefrom, a valve casing having a plurality of reciprocating valve plungers therein all disposed at one side of the cross-sectional middle of said handle, whereby digits of the hand of the operator may operate any one of said valves without changing the position of the hand on the handle, a valve outlet tube communicating with the interior of said valve casing and each of said valve plungers and having its open end adjacent the open end of said steam nozzle, each of said valve plungers reciprocally mounted in said valve casing, said valve casing provided with a bore portion having an enlarged and reduced portion, said valve plungers being mounted in the reduced portion having their head portions in the enlarged bore portion and gaskets near opposite ends of each of said valve plungers in said bore portions for sealing flow of fluid around said valve plungers.

2. In a spotting gun of the class described, the combination of a handle, a steam nozzle extending therefrom, a valve casing having a plurality of reciprocating valve plungers therein all disposed at one side of the cross-sectional middle of said handle, whereby digits of the hand of the operator may operate any one of said valves without changing the position of the hand on the handle, a valve outlet tube communicating with the interior of said valve casing and each of said valve plungers and having its open end adjacent the open end of said steam nozzle, each of said valve plungers reciprocally mounted in said valve casing, said valve casing provided with a bore portion having an enlarged and reduced portion, said valve plungers being mounted in the reduced portion having their head portions in the enlarged bore portion and gaskets near opposite ends of each of said valve plungers in said bore portions for sealing flow of fluid around said valve plungers, said valve casing provided with a common outlet bore communicating with each of said valve plungers.

3. In a spotting gun of the class described, the combination of a handle, a steam nozzle ex-

tending therefrom, a valve casing having a plurality of reciprocating valve plungers therein all disposed at one side of the cross-sectional middle of said handle, whereby digits of the hand of the operator may operate any one of said valves without changing the position of the hand on the handle, a valve outlet tube communicating with the interior of said valve casing and each of said valve plungers and having its open end adjacent the open end of said steam nozzle, each 10 of said valve plungers reciprocally mounted in said valve casing, said valve casing provided with a bore portion having an enlarged and reduced portion, said valve plungers being mounted in the reduced portion having their head portions 15 in the enlarged bore portion and gaskets near opposite ends of each of said valve plungers in said bore portions for sealing flow of fluid around said valve plungers, said valve casing provided with a common outlet bore communicating with each of said valve plungers, a plug screw threaded in each of said bore portions and a spring 20

engaging said plug and the head of the respective valve plunger adjacent thereto.
